Specification for Design.

Patented Dec. 17, 1918.

Application filed July 10, 1918. Serial No. 244,321. Term of patent 3½ years.

● *To all whom it may concern:*

Be it known that I, HERBERT A. SADLER, a citizen of the United States, residing at South Attleboro, county of Bristol, Commonwealth of Massachusetts, have invented a new, original, and ornamental Design for a Guard for the Ends of Knitting-Needles, of which the following is a specification, reference being had to the accompanying drawing, forming part thereof.

Figure 1—is a perspective view showing

the front portion and mouth of the pocket portion of my new design.

Fig. 2—is an edge view of the design.

Fig. 3—is an end view of the design showing the opening in the pocket.

Fig. 4—shows the back or reverse side of the design.

I claim:

The ornamental design for a guard for the ends of knitting needles, as shown.

HERBERT A. SADLER.
